(57) CLAIM

The ornamental design for a pair of earrings, as shown and described.

DESCRIPTION

FIG. 1 is a bottom rear right perspective view of an earring, showing my new design, the other earring of the pair of earrings being identical;

FIG. 2 is a right side elevational view thereof;

FIG. 3 is a left side elevational view thereof;

FIG. 4 is a top plan view thereof;

FIG. 5 is a bottom plan view thereof;

FIG. 6 is a rear elevational thereof; and,

FIG. 7 is a front elevational view thereof.

The broken lines shown in the drawings represent portions of the pair of earrings that form no part of the claimed design.

1 Claim, 7 Drawing Sheets
